BOTTLE WASHING MACHINE

2 Sheets-Sheet 2

INVENTOR:
ALBERT A. SMALLHOUSE,
BY *Albert A. Smallhouse*
ATTORNEYS.

UNITED STATES PATENT OFFICE.

ALBERT A. SMALLHOUSE, OF LOS ANGELES, CALIFORNIA, ASSIGNOR OF ONE-HALF TO
HORACE W. KELLEY, OF LOS ANGELES, CALIFORNIA.

BOTTLE-WASHING MACHINE.

Application filed August 11, 1926. Serial No. 128,590.

My invention relates to bottle washing machines, and the general object thereof is to provide an improved bottle washing machine which will be simple in construction, rapid and efficient in operation, and of such construction that the bottles may be readily placed therein for washing or removed therefrom when washed.

Other objects and advantages will appear hereinafter.

The invention is illustrated in the annexed drawings which form a part of this specification, and in which:

Fig. 1 is a vertical longitudinal section of one unit of the machine, with a bottle mounted therein and shown in longitudinal section.

Fig. 2 is a horizontal section taken on line 2—2 of Fig. 1.

Fig. 3 is a side elevation of a portion of the machine, showing a plurality of bottle washing units.

Fig. 4 is a horizontal section of the machine taken on line 4—4 of Fig. 3, showing the gearing of the machine.

Fig. 5 is a fragmentary vertical section of the brush showing the hinge joint between the vertical and upper brush members.

Corresponding reference characters designate the same parts in all the figures.

My invention may include a plurality of bottle washing units 1, which are mounted on a table 2. Each unit comprises a rotatable base 3 for supporting a bottle 4, bottle holding means 5, water injecting means 6 for injecting water into the bottle, and a brush 7 for wiping the interior of the bottle.

The base 3 is rotatably mounted on roller bearings 8 in a plate 9 which is countersunk in the upper side of the table 2 and bolted to the table by bolts 10 and nuts 11, there being an annular flange 12 formed on the upper side of said plate within which is turnably fitted the base 3. The base 3 is formed with an upper reduced end 13, and an external annular shoulder 14 at the base of said reduced end, on which reduced end is fitted a sprocket 15 which rests upon said shoulder and is secured to the base by bolts 16. The base 3 is provided with a central bore 17 while the plate 9 is provided with a center opening 18 coinciding with said bore. In the top of the base 3 is fitted an annular rubber gasket 19, the inner diameter of which coincides with the bore 17.

The water injecting means 6 comprises a coupling 20, a tube 21 connected at its lower end to the upper end of said coupling, and a water supply pipe 22 connected to the lower end of said coupling. The coupling 20 extends through the table 2, opening 18 in plate 9, bore 17 in rotatable base 3, and gasket 19, and is secured to the table by means of screws 23 extending through a flange 24 which is formed on the lower end of the coupling 20 and is drawn against the under side of the table by said screws. A packing ring 25 is fitted tightly on the coupling 20 in an annular rabbet 26 in the under side of the plate 9 against the table 2, which prevents leakage of water or oil from the bearings 8 below the same.

A gasket 27 is secured in the base 3 in contact with the coupling 20 to prevent water leaking down through the bore 17 into the bearings 8. The bore 28 of the coupling 20 is off-set at its upper end, as at 29, where the tube 21 is connected to the coupling, so that one side 30 of the tube coincides with the center of the rotatable base 3 and bottle holding means 5. The tube 21 is provided with perforations 31 the greater portion of its length through which water is injected from the tube into the bottle 4.

The brush 7 comprises a pair of brush members 32 and 33 and an intermediate vertical brush member 34. The member 32 comprises an arm 35 and bristles 36 secured in the lower side of said arm, while the member 33 comprises an arm 37 and bristles 38 secured in the upper side of said arm. The arms 32 and 33 are each made in two sections 39 and 40, the section 40 being bifurcated at one end at 41 to receive a tongue 42 on the adjacent end of the section 39, which tongue is provided with a longitudinal slot 43 to receive a screw 44 seated in the bifurcated end 41 of section 40, whereby the arms 35 and 36 may be adjusted in length and secured in adjusted positions.

The arm 35 is pivoted at one end of its section 39 to the side 30 of the tube 21 near the lower end of said tube at 45. The arm 37 is pivoted at one end of its section 39 to the upper end of the tube 21 at 46 in the upper end of a cap 47 which closes the upper end of the tube 21. The brush member 34 comprises a tubular bar 48 and

bristles 49 secured in the outer side thereof. The lower end of the bar 48 is pivoted at 50 to the outer end of the section 40 of arm 35.

5 The upper end of the bar 34 is pivotally connected to the outer end of the arm section 40 by means of hinge joint 51, which includes a pivot 52, a socket bearing 53 in the outer end of said section in which said 10 pivot turns, a wire 54 connected at its upper end to said pivot and extending downwardly in the upper end of bar 48, and a spring 55 in said bar connected at its upper end to the lower end of said rod, and at its 15 lower end to a pin 56 secured in the bar.

16 The section 40 is cut away below the socket bearing 53 at 57 to accommodate the wire 54 so that the brush members 33 and 34 may fold together, as shown in dotted 20 lines in Fig. 1. A flat spring 58 is secured at its upper end at 59 to the inner side of the bar 48 and bears at its lower end at 60 upon the upper side of the lower arm 35, which spring normally holds the connected 25 ends of the brush members 32 and 34 swung out slightly, as shown in dotted lines in Fig. 1, so that the brush may be easily unfolded in wiping position when the bottle is placed over the brush in the unit 1.

30 The bottle holding means 5 comprises a plurality of rods 61, preferably four in number and rubber sleeves 62 fitted on the upper ends of said rods. Said rods are secured in the top of the base 3, equi-distant 35 apart, by set screws 63, at a sufficient distance from the center of the base to accommodate the mouth and neck of the bottle 4, and the rods 61 are bent outwardly at 64 and then upwardly at 65, so that the rubber sleeves 62 will engage the side of the bottle 40 and hold the same with the mouth thereof resting upon the gasket 19.

40 In the base 3 of each unit 1 are provided radial outlets 66, leading from the bore 17 45 to the periphery of the base through which water may pass from the bore above the packing 27 out of the base. In the table 2, adjacent each base 3 is provided an outlet 67, which communicates with a drain pipe 68 secured to the under side of the table, and leading into a tank 70 below the table.

50 A chain 71 extends over the sprockets 15 of the units 1 and over a sprocket 72 secured on a power driven shaft 73, which is driven by power through a belt 74 and a pulley 75 secured on the shaft. Idler sprockets 76 are journaled on shafts 77 secured in the table 2 and engage the chain 71 from the outside between the adjacent sprockets 15 for 60 holding the chain in engagement with the latter sprockets.

65 The operation of my machine is as follows. Before the bottles are placed in the units 1 the brush 7 is held folded up, as shown in dotted lines in Fig. 1. While thus folded a

bottle is placed in a unit inverted, the brush 7 passing through the mouth into the bottle and the bottle fitting between the sleeves 62 and arms 61 until the mouth of the bottle rests upon the gasket 19. The engagement 70 of the bottom wall of the bottle with the upper brush member 33, unfolds the brush downwardly until the bristles 36 of the brush engage the upper wall of the bottle, the bristles 49 engage the side wall and the 75 bristles 38 engage the bottom wall of the bottle, as shown in full lines in Fig. 1. Water under pressure is introduced through pipe 22, coupling 20, tube 21 and its perforations 31 into the bottle.

80 Power being applied through belt 74 and pulley 75 to the shaft 73, the sprocket 72 is rotated, which through chain 71 rotates the sprockets 15 and bases 3 of the units 1, together with the holding means 5 and the 85 bottles 4 in said units. The rotation of the bottles causes the brush 7 to wipe the interior of the bottles 4 and wash the same with water until thoroughly cleaned. The water escapes from the bottles through the 90 mouths thereof and through bore 17, outlets 66, outlets 67 and drains 68 into the tank 70. When washed the bottles may be lifted out of the units, the brushes 7 folding to permit the same to pass out through the mouths of 95 the bottles.

96 By loosening the screws 44 the arms 35 and 37 may be extended or shortened, so that the brush will wipe bottles of different diameters, and when so adjusted the brush may be secured in such position by tightening said screws.

100 It will be understood that I may change or modify my invention within the scope of the appended claims, without departing from 105 the spirit thereof.

What I claim is:

1. In a bottle washing machine, a rotatable base for supporting and rotating a bottle, stationary water injecting means extending 110 upwardly from said base to be introduced into the bottle, a collapsible brush comprising three brush members, two of said brush members being pivotally connected to and extended radially from said stationary 115 means, a third brush member being pivotally connected to the free ends of said first two brush members so that the brush may be expanded when the bottle is placed on said rotatable base, to enable the brush to wipe the interior of the upper, lower and side walls of the bottle, respectively, and means for adjusting the brush to wipe bottles of 120 different diameter.

125 2. In a bottle washing machine, a rotatable base for supporting and rotating a bottle, stationary water injecting means extending upwardly from said base to be introduced into the bottle, a collapsible brush comprising three brush members, two of said brush 130

- members being pivotally connected to said stationary means, a third brush member being pivotally connected to the free ends of said first two brush members so that the brush may be expanded when the bottle is placed on said rotatable base, to enable the brush to wipe the interior of the upper, lower and side walls of the bottle, respectively, each of said first two brush members being formed into sections, and means for adjusting said sections with relation to each other to vary the length of said first two brush members, to enable the brush to wipe bottles of different diameters.
3. In a bottle washing machine a rotatable base for supporting and rotating a bottle, stationary water injecting means upstanding from said base, to be introduced into the bottle, a collapsible brush composed of three members, two of said members being pivotally connected to said stationary water injecting means, and the third brush member being pivotally connected at its ends to the free ends of said first two brush members, the connection between one of said first two brushes and said third brush member comprising a socket bearing in one of said first two brush members, a pivot mounted to turn in said socket bearing, a rod connected at one end to said pivot and extending into said third brush member, and a spring in said third brush member connected to the other end of said rod, and to a fixed point in said third brush member.
4. In a bottle washing machine a rotatable base for supporting and rotating a bottle, stationary water injecting means upstanding from said base to be introduced into the bottle, a collapsible brush composed of three members, two of said members being pivotally connected to said stationary water injecting means, and the third brush member being pivotally connected at its ends to the free ends of said first two brush members, the connection between one of said first two brush members and said third brush member comprising a socket bearing in one of said first two brush members, a pivot mounted to turn in said socket bearing, a rod connected at one end to said pivot and extending
- into said third brush member, a spring in said third brush member connected to the other end of said rod and to a fixed point in said third brush member, and a spring for contracting the brush when the bottle is removed from said rotatable base.
5. In a bottle washing machine a rotatable base for supporting and rotating a bottle, provided with a central bore extending therethrough, and outlets extending from said bore, a hollow stationary coupling extending through the bore being of smaller cross sectional area than said bore in said rotatable base, a perforated tube secured to the upper end of said coupling, means connected to said coupling for injecting water therethrough and through said perforated tube into the bottle, and a brush mounted on said tube for wiping the interior of the bottle.
6. In a bottle washing machine a rotatable base provided with an axial bore, and with outlets leading from said bore, an annular gasket fitted in the upper end of said base around said bore, upon which the mouth of the bottle may be placed, means for holding the bottle when its mouth is placed on said gasket, a hollow stationary coupling extending upwardly through said bore in spaced relation thereto, a perforated tube connected to the upper end of said coupling to be extended into the bottle when mounted on said base, and a brush connected to said tube for wiping the interior of the bottle when rotated.
7. In a bottle washing machine a table, a rotatable base mounted on said table provided with an axial bore, and with outlets extending from said bore, a hollow stationary coupling extending through said table and said bore, said coupling being of smaller cross sectional area than said bore, a perforated tube connected to the upper end of said coupling adapted to extend into the bottle when mounted on said rotatable base, a brush mounted on said tube for wiping the interior of the bottle, said table being provided with an outlet for draining the water from the bottle discharged through said base.

ALBERT A. SMALLHOUSE.
